CLOTHESPIN

Walter L. Sigman, Columbus, Ohio

Application October 13, 1958, Serial No. 52,934

Term of patent 3½ years

(Cl. D17—3)

Fig. 1 is a side elevational view of a clothespin embodying my new design;

Fig. 2 is a front elevational view as seen from the right of Fig. 1; and

Fig. 3 is a rear elevational view thereof as seen from the left of Fig. 1.

I claim:

The ornamental design for a clothespin, as shown.
